UNITED STATES PATENT OFFICE.

EMILE ZAEPFEL, OF BUFFALO, NEW YORK.

ROLLER-MILL FOR GRINDING GRAIN, &c.

SPECIFICATION forming part of Letters Patent No. 243,052, dated June 14, 1881.

Application filed February 15, 1881. (No model.)

To all whom it may concern:

Be it known that I, EMILE ZAEPFEL, of the city of Buffalo, in the county of Erie, in the State of New York, have invented new and useful Improvements in Roller-Mills, of which the following is a specification, reference being had to the accompanying drawings.

This invention relates to that class of roller-mills which are employed for grinding and crushing grain, and for similar purposes.

The object of this invention is to construct the mill in such manner that the rollers can be nicely adjusted and adapted to the work which they are required to perform.

My invention consists, to that end, of the particular construction of the mechanism whereby the rollers are adjusted in the stationary frame in which they are mounted, as will be hereinafter fully set forth.

In the accompanying drawings, Figure 1 is a side elevation of my improved roller-mill with the driving-pulleys removed. Fig. 2 is a side elevation, showing the driving-pulleys in place. Fig. 3 is a top-plan view of the roller-mill. Fig. 4 is a vertical cross-section, on an enlarged scale, of one of the upper roller-bearings. Fig. 5 is a longitudinal section thereof.

Like letters of reference refer to like parts in the several figures.

A represents the lower parts of the stationary side frames; B, the upper parts thereof, and B' the caps, which are secured to the upper parts, B.

C C' represent two horizontal rollers arranged between the upper portions, B, of the side frames, and C² is a similar roller arranged between the lower portions, A, of the side frames and operating in conjunction with the roller C'. The upper rollers, C C', are journaled in bearings d d', which are made adjustable toward and from each other, between wedges D on the lower sides of the bearings and wedges E on their upper sides. The wedges D slide on inclines f, formed on the upper side of the bottom piece of the upper portion, B, of the side frame, and the wedges E bear against inclines g, formed on the lower side of the cap B'. The wedges D and E are adjusted by set-screws h, which work in threaded openings in the upright portions b of the upper portions, B, of the side frames, and are secured in place by jam-nuts i.

K represents a wedge, which is interposed between the inner inclined surfaces of the bearings d d', and which is made vertically adjustable by a set-screw, k, working in an opening in the cap B'. The bearing d is held against outward movement by a set-screw, l.

m represents a sliding bolt, which bears against the outer side of the bearing d' and moves loosely through an opening in the adjacent upright portion b of the upper portion, B, of the side frame.

M is a weighted lever, which is pivoted to the side frame at m', and which bears with its short arm m² against the bolt m, whereby the bearing d' is pressed inward or toward the bearing d and against the wedge K. The surfaces of the wedges D and E which are in contact with the bearings d d' form parallel ways, 70 between which the bearings slide toward and from each other. By adjusting the wedge K, the distance to which the bearings d d' and the rollers C C' can approach each other is increased or lessened as may be desired. After 75 adjusting the wedge K the set-screw l is adjusted to hold the bearing d stationary. The bearing d' is pressed against the wedge K by the weighted lever M and yields when a hard object of unusual size enters between the rollers, thereby avoiding injury to the rollers. The position of the rollers C C' is regulated vertically by adjusting the wedges D E.

n represents the bearing of the lower roller, C², made vertically adjustable between ways 85 o, which are formed in the lower portion, A, of the side frame. The bearing n is adjusted by set-screws p p.

Q Q' Q² are the driving-pulleys, respectively mounted on the shafts of the rollers C C' C², 90 the pulley Q being the smallest and the pulley Q' the largest, whereby the circumferential velocity of the roller C is made greater than that of the roller C², and the velocity of the latter greater than that of the roller C'. The 95 material is first reduced between the rollers C C' and drops then on the roller C², between which and the roller C' the material is reduced a second time. Power is transmitted to the pulleys Q Q' Q² by the same endless belt r. 100

The wedges D E are provided with overlapping flanges, which project over the sides of the bearings d d' and over the edges of the inclined ways on which the wedges slide, as

represented in Fig. 4, to prevent lateral displacement of the parts.

I claim as my invention—

1. The combination, with the roller-bearings $d d'$, of the wedges D E, arranged, respectively, between the lower and upper sides of the roller-bearings and inclined ways $f g$, formed in the side frames, whereby the roller-bearings are rendered vertically adjustable, and at the same time permitted to move horizontally toward and from each other, substantially as set forth.
2. The combination, with the roller-bearings $d d'$, of the wedges D E, arranged, respectively, between the lower and upper sides of the roller-bearings and inclined ways $f g$, formed in the side frames, and a vertically-adjustable wedge, K, arranged between the inner beveled sides of the bearings $d d'$, whereby the latter are rendered vertically adjustable and permitted to move horizontally toward and from each other, and their horizontal movement toward each other is limited, substantially as set forth.
3. The combination, with the roller-bearings $d d'$, of the wedges D E, arranged, respectively, between the lower and upper sides of the roller-

bearings and inclined ways $f g$, formed in the side frames, whereby the roller-bearings are rendered vertically adjustable, and at the same time permitted to move horizontally toward and from each other, a vertically-adjustable wedge, K, arranged between the beveled inner sides of the bearings $d d'$, and a weighted lever, M, whereby the bearings $d d'$ are pressed against the wedge K and permitted to recede therefrom when an object of improper size and hardness enters between the rolls, substantially as set forth.

4. The combination, with the roller bearings $d d'$, of the wedges D E, arranged, respectively, between the lower and upper sides of the roller-bearings and inclined ways $f g$, formed in the side frames, a vertically-adjustable wedge, K, arranged between the beveled inner sides of the bearings $d d'$, and the bearings n of the third roller made vertically adjustable in the side frames, substantially as set forth.

EMILE ZAEPFEL.
